AUTOMATIC SPRINKLER VALVE

Harry N. Rider, Youngstown, Ohio, assignor, by
mesne assignments, to "Automatic" Sprinkler
Corporation of America, Youngstown, Ohio, a
corporation of Delaware

Application May 13, 1947, Serial No. 747,805

4 Claims. (CL 169—19)

1

This invention relates to automatic sprinkler systems for fire protection purposes and more particularly to an automatic valve forming the control element for the fire extinguishing fluid in an automatic sprinkler system.

The principal object of the invention is the provision of an automatic valve which may be incorporated in a dry pipe sprinkler system, a pre-action sprinkler system, a deluge type sprinkler system or a thermostatically actuated rate-of-rise sprinkler system.

A further object of the invention is the provision of an automatic valve which incorporates novel means for holding the clapper thereof in normally closed position.

A still further object of the invention is the provision of an automatic valve for a sprinkler system and incorporating novel pilot valve mechanism therein.

A still further object of the invention is the provision of an automatic valve for a sprinkler system which may be modified for installation in various types of automatic sprinkler systems by the substitution of various actuating mechanisms, any and all of which are capable of actuating the mechanism of the automatic valve.

The automatic valve for sprinkler systems shown and described herein has been designed to provide a universal type valve which may be generally employed in dry pipe sprinkler systems in which the distributing piping of the automatic sprinkler system is either empty or normally filled with supervisory air pressure. The automatic valve is equally capable of installation and satisfactory operation in a preaction type sprinkler system in which thermostatic means is employed for actuating the automatic valve in advance of the opening of the automatic sprinklers on the distributing piping.

The automatic valve is also capable of installation and efficient operation in connection with a rate-of-rise deluge type sprinkler system in which a separate thermostatic system is used to actuate the valve and in which the sprinklers on the distributing piping are always open.

It will be obvious to those skilled in the fire protection art that an automatic valve capable of installation and satisfactory operation in several types of automatic sprinkler systems is novel in the art and highly desirable, as it enables the realization of substantial savings in manufacturing operations, as the one valve may be manufactured and used in all of the sprinkler systems, the actuating means only being changed in the several types of systems.

2

As disclosed herein, the automatic valve is illustrated in connection with a low air pressure dry pipe sprinkler system although it may be equally advantageously employed in preaction, deluge and rate-of-rise actuated sprinkler systems as well.

With the foregoing and other objects in view which will appear as the description proceeds, the invention resides in the combination and arrangement of parts and in the details of construction hereinafter described and claimed, it being understood that changes in the precise embodiment of the invention herein disclosed can be made within the scope of what is claimed without departing from the spirit of the invention.

The invention is illustrated in the accompanying drawing, wherein:

Figure 1 is a side view of the automatic sprinkler valve.

Figure 2 is a vertical cross section taken on line 2—2 of Figure 1.

Figure 3 is a front view of the automatic valve shown in Figures 1 and 2 and an associated low air pressure dry pipe sprinkler actuating means, portions of the view being broken away and parts thereof in cross section.

By referring to the drawings and Figures 1 and 2 in particular, it will be seen that the automatic valve comprising a body 10 has been disclosed in normal operative position between a gate valve 11 and a riser 12, the gate valve 11 also being in communication with a fluid supply source, not shown, and the riser 12 being in communication with and forming a part of the distributing piping of an automatic sprinkler system.

The automatic valve has a plurality of access opening covers 13, 14 and 15, respectively, two of which, the access opening covers 13 and 15, are secured to the valve body 10 in registry with access openings therein by means of a plurality of stud and nut assemblies 16 and 18, respectively, the access cover 14 being secured by a plurality of cap screws 17. Gaskets 19, 20 and 21 insure the water-tight positioning of the access covers 13, 14 and 15, respectively and in connection with the valve body 10 form a water-tight enclosure in which a clapper 22 is pivotally positioned by means of a hinge pin 23. The clapper 22 is provided on its lowermost face with an annular cross sectionally U-shaped self-sealing gasket 24 which is adapted to register with an inlet ring 25 forming the inlet orifice of the automatic valve.

A plurality of bosses 26 are formed on the inner surface of the valve body 10 and are adapted to

register with a hinged arm 27 on the clapper 22 so as to prevent the clapper 22 from reseating once it has opened. The clapper 22 is also provided with a latch projection 28 so positioned that it clears the bosses 23 when the clapper 22 opens and pivots about the hinge pin 23 and provides means upon which a pivoted latch member 29 may be engaged when the clapper 22 is in closed position with respect to the inlet ring 25. The latch member 29 is pivotally mounted in the valve body 10 adjacent the clapper 22 by means of a pivot pin 30. A latch link 31 is pivotally affixed to the latch member 29 by means of a pivot pin 32 and is also affixed to the inner adjustably positioned end of a diaphragm engaging secondary latch link 33 by means of a secondary pivot pin 34. The diaphragm engaging latch link 33 is passed through an opening in a diaphragm 35 and secured thereto to form a water-tight closure with respect to the said opening in the diaphragm 35. The opposite end of the diaphragm engaging latch link 33 extends outwardly through an opening in the access opening cover 14 and has a pair of annular flanges 36 formed thereon so that longitudinal motion may be imparted thereto by means suitable for engagement therewith between the said annular flanges 36.

It will thus be seen that the diaphragm 35 and the diaphragm engaging latch link 33 comprise means by which motion from the exterior of the valve body 10 may be conveyed to the interior of the valve body 10 and at the same time maintain a water-tight closure with respect thereto. It will be obvious to those skilled in the art that several forms of releasing devices may be employed for imparting motion to the diaphragm engaging latch link 33 so as to move it and the latch link 31 and latch member 29 away from the projection 28 on the clapper 22 when it is desired to unlatch and thereby open the said automatic valve.

By referring to Figure 2 of the drawings in particular, the foregoing mechanical latch members may be most advantageously seen and it will also be observed that a pilot valve mechanism incorporated in the valve body 10 is operated by the clapper unlatching mechanism heretofore described. The pilot valve mechanism includes an inlet orifice 37 and an outlet orifice 38 and a valve seat 39 disposed in the inlet orifice and extending into a pilot valve chamber 40 with which the outlet orifice 38 communicates. The pilot valve chamber 40 is formed in the valve body 10 and is closed with respect thereto by a threaded plug 41 which is provided with a centrally located opening 42 through which a rod 43 is slidably positioned. The inner end of the rod 43 carries a valve element 44 adapted for registry with the valve seat 39 and the outer end of the rod 43 is provided with a pair of spaced annular flanges 45 so that longitudinal motion may be imparted to the valve rod 43 by suitable means such as a lever 46 which is pivoted to the valve body by means of a pivot pin 47 and has one end thereof loosely engaging the valve rod 43 between the spaced annular flanges 45 and the other end thereof lying adjacent a projection 48 on the latch member 29 heretofore referred to.

It will thus be seen that when the latch member 29 is in engagement with the projection 28 of the clapper 22 so as to hold the clapper 22 in closed position on the inlet ring 25 of the automatic valve, the projection 48 on the latch member 29 will move upwardly and outwardly against the upper end of the pivoted lever 46 and hence

impart inward movement to the opposite end thereof and hence to the valve rod 43 so that the valve element 44 registers with the seat ring 39 and thereby closes the inlet orifice 37 to the pilot valve chamber 40. A bellows 49 is affixed to the valve element 44 and the threaded plug 41 to provide a water-tight flexible connection between the valve element 44 and/or the valve rod 43 and the plug 41.

It will thus be seen that at such time as motion is imparted to the valve operating mechanism to move the latch mechanism to the right as shown in Figure 2 of the drawings, and thereby move the latch member out of engagement with the projection 28 of the clapper 22, the projection 48 on the latch member 29 will move downwardly and out of engagement with the pivoted lever 46 and thus permit fluid pressure in the inlet 37 of the pilot valve to move the valve member 44 to the right, as shown in Figure 2 of the drawings, and hence establish communication with the pilot valve outlet orifice 38 heretofore referred to.

In actual sprinkler system practice, a water motor alarm is in communication with the outlet orifice 38 and/or a pressure switch may be incorporated in this connection so that in addition to or in place of the water motor alarm an electrical signal audible or visual as desired, may be given at such time as the clapper 22 in the automatic valve is unlatched and opened by fluid pressure in the inlet thereof.

It will be observed that all of the various operating parts of the clapper 22 and the pilot valve element 44 are of simple formation and thereby capable of long trouble-free life in operation and further that they are all accessible for both initial assembly and subsequent inspection and resetting operations by the conveniently placed access opening covers 13, 14 and 15 heretofore referred to.

The foregoing description of the automatic valve will enable those skilled in the art of fire protection to recognize the several advantages and points of novelty in the disclosed valve structure and its ability to be incorporated in several different types of automatic sprinkler systems. As an example of the interchangeability of the automatic valve herein disclosed with respect to various sprinkler systems, it has been illustrated in Figures 1 and 3 of the drawings in operative arrangement with a low air pressure dry pipe sprinkler system valve actuating mechanism responsive to loss of low air pressure in the distributing piping of the sprinkler system as occasioned, for example, by the opening of one or more of the automatic sprinklers in communication with the said distributing piping of such a sprinkler system.

By referring to Figures 1 and 3 of the drawings it will be seen that the operating mechanism engages the diaphragm engaging latch link 33 of the automatic valve, as heretofore described, between the spaced annular flanges 36 thereon in a manner so that suitable movement may be imparted thereto and hence to the latch member 29 to enable it to be disengaged from the projection 28 of the clapper 22 of the automatic valve.

In Figures 1 and 3 of the drawings, the access cover plate 14 is illustrated and it will be observed by referring thereto that a pair of spaced projecting arms 50 are formed thereon, one on each side of the projecting diaphragm engaging latch link 33 and therebelow so that an L-shaped striking lever 51 may be pivoted to the arms 50 as by a pivot pin 52 and so that it engages the dia-

phragm engaging latch link 33 by means of the spaced annular flanges 36 thereon as inturned end portions 53 of the striking lever 51 are positioned therebetween. The outermost end 54 of the striking lever is bifurcated and has a pivot pin 55 positioned transversely thereof and engaged with the lower end of a weight guide rod 56. The said guide rod 56 is positioned vertically in a housing 57 which in turn is affixed to the valve body 10 by a plurality of bolts 58 which engage the valve body 10 immediately about the periphery of the access cover 14 heretofore referred to. The housing 57 slidably supports the upper end of the guide rod 56 in a bushing 59 and a weight 60 is slidably positioned on the guide rod 56 and normally held in elevated relation thereon and with respect to the striking arm 51.

The center portion of the weight 60 is cut away so that when it drops downwardly along the weight guide rod 56 a striking plate 61 of the weight engages the bifurcated end 54 of the striking lever 51. Means for normally sustaining the weight 60 in the housing 57 and in elevated relation on the weight guide rod 56 is provided and is illustrated in detail in Figure 3 of the drawings and comprises an improvement over that shown in my patent on Dry pipe valve, Patent Number 2,251,422, issued August 5, 1941. The releasing mechanism includes an air pressure chamber 62 formed by a pair of oppositely disposed body portions 63 and 64 which are united with one another in opposed relation and attached to the housing 57 by means of a plurality of cap screws 65. The body member 64 has a circular opening therein and an annular flange 66 thereabout, the inner surface of which is threaded and adapted to receive a threaded adjustment member 67. The diaphragm is positioned in the chamber 62 and across the opening in the body member 64 and is normally urged toward the opening by reason of air pressure in the chamber 62 which is in communication with the riser of a dry pipe sprinkler system by way of an orifice 69. A coil spring 70 is positioned between the adjusting member 67 and a re-enforcing plate 71 on the back of the diaphragm 68 and a latch rod 72 is affixed to the diaphragm 68 and the re-enforcing plate 71 and extends through the coil spring 70 and an opening in the adjustment member 67 and outwardly therefrom wherein an adjustable tip portion 73 thereof serves as a detent in restraining a pivoted lever 74. The pivoted lever 74 is pivotally mounted between a pair of arms 75 formed on the body member 64 and a portion of the pivoted lever 74 registers with a spring urged latch 76 which in turn is pivoted by means of a pivot pin 77 to the weight 60.

Thus, loss of air pressure, for example one and one-half or two pounds from the distributing piping of a dry pipe sprinkler system (not shown) in communication with the chamber 62 as occasioned by the fusing of an automatic sprinkler on the dry pipe sprinkler system permits the coil spring 70 to move the diaphragm 68 and its supporting plate 71 inwardly of the chamber 62 so as to slide the latch rod 72 longitudinally to the left in Figure 3, and thereby permit the pivoted lever 74 to turn clockwise about its pivot and thus release the spring urged latch 76 and hence the weight 60. The weight 60 in dropping will strike the bifurcated end section 54 of the striking lever 51 and impart the necessary motion to the valve unlatching mechanism heretofore described.

In resetting the valve and its dry pipe operating mechanism, as described herein as an example

of one of its uses, it is necessary to close the gate valve 11, open the access cover 13 of the valve and reseat the clapper 22 thereof. When this is done, the pilot valve member 44 will be automatically closed as heretofore described and suitable air pressure may again be established in the distributing piping of the associated sprinkler system when the fused sprinklers are replaced. When the desired air pressure is restored, the weight 60 may be re-engaged upon the pivoted lever 74 and upon the reopening of the gate valve 11, the sprinkler system and automatic valve therein is again ready for operation.

It will thus be seen that the automatic valve disclosed herein is capable of simple and efficient operation in a low air pressure dry pipe sprinkler system and it will be obvious to those skilled in the art that it is equally adaptable to and efficient in use in various thermostatically actuated sprinkler systems of either the preaction or deluge type wherein the actuating mechanism herein disclosed is not employed and a different form of weight releasing device, such as known in the art is employed by attaching the same to the valve in the manner of the weight releasing mechanism herein disclosed.

It will be equally apparent to those skilled in the art that the several objects of the invention are met by the automatic valve disclosed herein.

Having thus described my invention, what I

claim is:

1. In a valve for an automatic sprinkler system comprising a valve body having a clapper hinged therein adapted to close a water inlet therein and a movable latch member for maintaining the clapper in closed position; a pilot valve in said valve body and a pivoted lever operatively engaging the said pilot valve and the said latch member for opening the said pilot valve when the said latch member is moved to release the said clapper.

2. In a valve for an automatic sprinkler system comprising a valve body having a clapper hinged therein adapted to close a water inlet therein and a movable latch member for maintaining the clapper in closed position; a pilot valve in said valve body and a pivoted lever operatively engaging the said pilot valve and the said latch member for opening the said pilot valve when the said latch member is moved to release the said clapper, and means for transmitting motion from the exterior of the said valve body to the said latch member, said means including a diaphragm forming a wall of the said valve body and movable means affixed to said diaphragm and to said latch member.

3. In an automatic valve for a sprinkler system comprising a valve body having a clapper hinged therein adapted to close a water inlet therein and movable latch means for normally maintaining the clapper in closed position; a pilot valve chamber formed in said valve body and a pilot valve inlet establishing communication between the said water inlet and the pilot valve chamber, and a pilot valve outlet establishing communication between the said pilot valve chamber and the exterior of the said valve body, a valve element in said pilot valve chamber, a pivoted lever in said valve body engaging said movable latch means and said valve element for operating the said valve element when the said latch means is moved.

4. In an automatic valve for a sprinkler system and comprising a valve body having a clapper hinged therein adapted to close a water inlet therein and movable latch means for normally

maintaining the clapper in closed position; a pilot valve chamber formed in said valve body and a pilot valve inlet establishing communication between the said water inlet and the pilot valve chamber, and a pilot valve outlet establishing communication between the said pilot valve chamber and the exterior of the said valve body, a valve element in said pilot valve chamber, a pivoted lever in said valve body engaging said movable latch means and said valve element for operating said valve element when the said latch means is moved, and means for transmitting motion from the exterior of the said valve body to the said latch means, said means including a

diaphragm forming a wall of the said valve body and movable means affixed to said diaphragm and to said latch means.

HARRY N. RIDER.
